Application March 29, 1949, Serial No. 84,166

9 Claims. (Cl. 75—74)

1

This invention relates to a method of feeding or charging metallurgical furnaces, and more particularly is concerned with a procedure for introducing the raw materials to be smelted into a reverberatory furnace used for producing copper matte.

Various devices and procedures have been used heretofore for feeding reverberatory furnaces. Generally, such furnaces are operated continuously in that the furnace is not emptied between charges but a molten bath is maintained in the furnace at all times between the time of starting up the furnace and shutting it down for repairs or some other reason.

One method of feeding such a furnace that has been used was the introduction of the charge through holes or ports in the center of the furnace roof or arch, allowing the charge to fall by gravity down into the bath. This center feed method could be used only for dry material however, and in more recent years has been largely superseded by the side feeding furnace.

The charging openings in the side feed furnaces are located at the edge of the arch along the skewback so that the charge piles up in sloping heaps along the interior side walls of the furnace. This was adopted with a view to protecting the side walls of the furnace and in an effort to approach continuous feeding and smelting. However, this method has the disadvantage of producing accumulations of solidified material on the floor or hearth of the furnace which gradually build up and reduce the size of the molten bath. Such solid accumulations include charged material that has never been melted but that has been forced down through the bath to a point where the temperatures are too low for melting, and other material which has separated out of the bath as a refractory substance.

The so-called gun-feed bath furnace has also been used with hot dry raw materials, and in this case the hot dry feed is introduced by gravity through retractable inclined conduits or pipes inserted through the side walls of the furnace so that they discharge at an elevation only a few inches above the surface of the bath and cause the calcine to spread over the surface of the bath. Such a feeding method, however, could not be used for moist or wet material.

In recent years, there has been considerable use of the reverberatory furnace to melt down concentrates from copper ore, these concentrates being unroasted and often moist, and in some cases even wet. This development was brought about by progress in the ore dressing

2

field and the upgrading of concentrates from copper ore to such an extent that it became no longer necessary to roast the concentrates preliminary to smelting in order to make a copper matte of the desired high copper content for converting directly to blister copper.

By this procedure the three-step process of roasting, melting and converting has been reduced to a two-step process of melting and converting. However, because wet materials in contact with molten matte produce violent explosions it has been apparent that the old center feed or gun feed type of furnace could not be used, and the charging of such material has had to be confined to the side feed furnace with its attendant disadvantages. However, even with this method of feeding, operators are troubled by the fact that explosions do occur unless the greatest of care is exercised to prevent any substantial quantity of wet material from slipping down or rolling off the inclined heap of charge along the sides of the furnace and plunging into the bath.

Also, such moist or wet unroasted concentrates are not provided with adequate flux for the silicious matter, such as the iron oxide which is present in a roasted ore or concentrate, and this necessarily makes difficult the practice of smelting raw or wet sulfide concentrates in the reverberatory furnace. The fluxing of the non-sulfide or silicious portion of the charge is very hazardous with the side feeding method. In the two-stage melting-converting process all of the iron sulfide in the reverberatory furnace charge must be oxidized in the final or converting step and all of the iron oxide produced in the converter is returned at infrequent intervals to the reverberatory furnace in the form of molten converter slag.

For the best metallurgical results, such converter slag must not only be combined with additional silicious material to increase its silicate content to the point where it can be economically disposed of as reverberatory furnace slag, but also the condition of super-oxidation in which it arrives at the reverberatory furnace must be reduced by proper high temperature contact with sulphide or other reducing agent. These results are not properly accomplished in the side feed reverberatory furnace and the converter slag is likely to flow forwardly in the furnace more or less along the center line thereof and thus pick up only in a haphazard fashion the needed silica and sulfide material with which it should react. Another difficulty inherent in the side feed fur-

nace for the treatment of raw or wet concentrates is that it does not lend itself to steady continuous feeding. All sulfide concentrates contain some volatile sulfur, and if substantial amounts of pyrite are present, this sulfur has substantial fuel value which should be utilized. The side feed furnace does not permit uniform control of the combustion of the sulfur as shown by the fact that even under the best operating conditions, sulfur vapor is usually present in the furnace exit during part of the cycle while free oxygen is present in other parts of the cycle. In attempting to proportion combustion air to the regular furnace fuel plus the irregular sulfur supply, the furnace operator is compelled to operate with appreciable thermal inefficiency. This in turn means that it is not possible to melt nearly as much solid charge as the furnace is theoretically capable of smelting.

One object of my invention is the provision of a method of feeding a reverberatory furnace which makes bath smelting applicable to raw moist charges without explosion hazards and without the necessity of expensive and laborious pre-mixing or bedding the charge of raw materials.

A further object of this invention is the provision of a reverberatory furnace feeding method for the direct melting of sulfide concentrates which provides better fluxing of the charge, better reduction and treatment of converter slag, less iron in the matte and less copper loss in the reverberatory furnace slag.

Another object of my invention is to provide such a furnace feeding method for moist concentrates which improves the utilization as fuel of the volatile sulfur content of the concentrates.

A still further object is the provision of such a feeding method which permits the charge to be fed more continuously and makes possible a reduction in labor and in fuel consumption as well as an increase in the smelting capacity of the furnace.

These objects and advantages will be more readily understood from the following description of my invention in conjunction with the accompanying drawings, in which:

Fig. 1 is a general plan view of a copper reverberatory furnace equipped for operation according to my invention.

Fig. 2 is a side elevational view of such a copper reverberatory furnace.

Fig. 3 is a transverse sectional view through such a furnace, taken approximately on the line 3—3 of Fig. 2.

Fig. 4 is a side elevational view, partly in section, showing one form of charging device mounted for use according to my invention.

Fig. 5 is a sectional view through such a charging device, taken approximately along the offset line 5—5 of Fig. 4.

Fig. 6 is a plan view of the charging device illustrated in Figs. 4 and 5.

Figs. 7, 8, 9 and 10 are side elevational views, partly in section, showing other forms of charging devices that can be utilized for feeding a furnace according to my invention.

I have found that the foregoing objectives and advantages can be accomplished by forming a molten bath in a reverberatory furnace, and spreading or distributing over the surface of the bath the raw materials charged into the furnace to produce a layer that will not submerge, sink or plunge so as to bring wet or moist materials in contact with the molten matte. This layer,

which floats on or near the surface of the bath, is preferably maintained at such a thickness that rapid smelting will be promoted by the exposure of its upper surface to the flame in the furnace and its under surface to the stored up heat in the molten bath. Moist or wet concentrates can thus be charged into a furnace as well as fluxing and other materials. The charge may be pre-mixed, although it does not have to be and the different materials can be charged in separately. Suitable fluxes, reducing agents or other materials may be introduced as separate layers when needed and the entire layer or blanket of the charge may be continuously or intermittently replenished at the will of the operator, thus making the method unusually flexible.

This method also permits much more efficient handling of the molten converter slag since a layer of appropriate silicious flux with or without a sulfide or carbonaceous reducing agent may be established on the surface of the bath in the area near the port through which the molten converter slag is introduced into the furnace.

Referring now to Figs. 1, 2 and 3 of the drawings, numeral 11 indicates generally a reverberatory furnace for smelting copper ores or concentrates in accordance with my invention. This furnace may be constructed with the concrete and cast slag foundation 12 and 13 reinforced as necessary by suitable tie rods. The furnace may also be provided with the crucible 14 and formed with refractory side walls 15, arch or roof 16, and end walls 17 made and lined with any desired type of refractories.

One end of the furnace is provided with ports 18 for the burners used to fire the furnace, and provision may be made for one or more uptakes 19 at the other end of the furnace to carry off the exit gases.

The furnace may also be provided with the customary slag skimming launder 20 to deliver the reverberatory furnace slag directly into a slag pot 21, the usual matte tapping spouts 22 for drawing off matte directly into the ladles 23, and the launder 24 for the introduction of converter slag into the reverberatory furnace.

In accordance with my invention, the side walls of the furnace are preferably provided at appropriate intervals with charging ports 25, and if desired an additional charging port 26 may be provided in the end wall of the furnace near the port communicating with the converter slag launder 24. Vertically sliding doors 25a may be used to cover these ports when they are not being employed for charging the furnace.

Platforms 27 supported by suitable superstructure 28 may be arranged along the walls of the furnace opposite these charging ports 25 and 26, so that charging devices such as shown at 29 may be properly positioned, adjusted and operated for charging the furnace. Raw materials to be introduced into the furnace may be handled in portable containers 30 which can be positioned on platforms 27a above the feeding hoppers 31 used with variable-speed conveyors 31a for delivering the raw materials to the charging devices 29.

The portable containers 30 may be readily shifted from one position to another as desired by means of an overhead crane and each individual container may, if desired, be filled with different material to be charged, such as moist concentrates, silica, crushed lime rock, or whatever is to be fed into the furnace from time to time.

Reference is now made particularly to Figs. 4, 5 and 6 which illustrate one form of charging

device 29 suitable for feeding a furnace in accordance with my method. This slinging type of charging device may consist of a carriage 32 mounted on wheels 33 so that it can be moved up into position adjacent the charging ports 25 or 26 for feeding material into the furnace, or can be retracted to a position back some distance from the furnace side wall when it is not being used for feeding. The carriage 32 may have an upper plate 34 which supports similar plate 35 for rotation about the central axis or spindle 36. Plate 35 in turn has bolted thereto the vertical arms 37 which support the frame 38 of the slinging device for rotation on trunnions about a horizontal axis.

The slinging device itself may consist of an endless belt 39 driven by the motor 40 and supported by the pulleys or rollers 40a, 41 and 42 to hold the belt in contact with the distributing wheel 43.

The distributing wheel 43 is preferably constructed with radially extending side flanges 44 centrally connected by a cylindrical hub 45 of smaller diameter. The outer ends of the side flanges 44 are provided with flat surfaces 46 which bear directly against the outer edges of the belt 39, thus leaving an arcuate space bounded by the side flanges 44, the belt 39 and hub 45 where the belt is in contact with this wheel. A hopper or chute 47 is mounted above and to one side of the axle of the distributing wheel in such a manner as to deliver the raw material 48 into the upper end of this arcuate space. Thus, as the raw material is brought into contact with the rapidly moving belt, it is formed into a compact stream and propelled by the belt into the furnace along a very flat trajectory.

The frame 38 of the charging device which carries the motor 40, the belt 39, pulleys 41 and 42, distributing wheel 43 and hopper 47, is arranged to be rotated or tilted as a unit about a horizontal axis by reason of the support of this frame on trunnions by the arms 37. In this manner the angle which the delivering portion of the belt 39 makes with the horizontal can be varied by tilting the charging device so that the pulley 42 is lowered or raised the required amount.

In addition, the entire charging device being supported on the rotatable plate 35 can be swung about a vertical axis so that the direction of the belt 39 is changed laterally. The charging device itself thus can be readily swung in a horizontal direction or tilted vertically by the operator using the handle 50 which is fixed to the frame 38 to direct the raw material as may be desired.

The motor 40 is preferably designed to operate the belt at a fairly high speed so that a more or less compact ribbon of raw material, as illustrated at 51, may be delivered continuously from the end of the belt and propelled or projected through the charging ports 25 or 26, into the furnace. Vertical tilting of the charging device will of course change the angle and therefore the distance that this raw material is thrown into the furnace. Dot-dash lines 52 indicate a position in which the material is projected a considerable distance into the furnace, whereas the stream 51 is illustrated as being delivered onto the surface of the molten bath at a point fairly close to the side wall 15.

In any case the materials charged preferably are thrown so as to hit the surface of the bath at a low angle and in the form of a more or less compact stream. This avoids submersion or

plunging of the raw materials below the surface of the molten bath.

Instead of the slinging device illustrated in Figs. 4, 5 and 6, other devices may be used to feed moist or wet concentrates and other moist or dry raw materials into a reverberatory furnace to spread or distribute these raw materials over the surface of the molten bath in accordance with my invention.

Fig. 7 illustrates a rotary disc type of slinging device which may be used for moist or dry materials and is shown mounted upon a retractable wheeled carriage 55. In this case the device consists essentially of a rotatable disc 56 mounted on a frame 57 that is arranged to tilt about a horizontal axis. Disc 56 may be rotated at a reasonably high speed by the motor 58. Mounted above the disc 56 so that its lower edge just clears the disc surface is a stationary cylindrical shell 59 supported by the shaft 60. The shell 59 preferably has an opening 61 adjacent the charging port 25 in the furnace side wall 15 and is provided with a fixed plow element 62 at one side of the opening 61. Thus, as wet concentrates or other raw material are delivered onto the surface of the disc 56 from the spout 63, the rotating disc brings this material around at high speed to a point where it is caught by the plow 62 and directed out through the opening 61. Centrifugal force thus serves to project the material into the furnace.

If desired, the cylindrical shell 59 may be made adjustable to swing the opening 61 to one side or the other and thus provide some lateral adjustment under the control of the operator, and of course tilting the disc 56 about a horizontal axis provides the operator with some flexibility of control in the distance that the raw material is projected or propelled into the furnace.

Another form of charging device which is illustrated in Fig. 8 consists of a frame 65 mounted on a retractable carriage 66, the frame 65 being rotatable about a vertical axis. Frame 65 supports on trunnions for vertical tilting a pneumatic discharge tube 67 which is provided at its upper portion with a feed hopper 68 to receive the wet concentrates or other raw materials from the delivery hopper 69. Compressed air or other gas may be supplied to the device through the hose 70 controlled by the valve 71. The inner end of the hose 70 may be provided with a tapered nozzle 72 to serve as an injector for entraining and forcing the raw materials out the end of the tube 67. The operator may easily adjust the vertical angle of throw or lateral angle of distribution of the charge by means of the handle 73.

Another form of charging device is illustrated in Fig. 9 and consists essentially of a motor driven centrifugal pump 75 supported on a suitable retractable carriage 76. A pumpable mixture of slurry of the raw material to be charged into the furnace is delivered to the pump through the inlet 77 and is discharged through the flexible hose 78 and a rigid nozzle 79 of any suitable length. Thus, by moving the nozzle 79 around to different positions, and preferably by holding the end of the nozzle close to the surface of the molten bath of the furnace, the operator can deliver a continuous compact stream of raw material onto the surface of the bath and distribute or spread this material around at will.

A still further form of charging device is illustrated in Fig. 10 and consists essentially of an extruding chamber 80 mounted on a retract-

able carriage 31 and driven through suitable reduction gearing by the motor 32. The extruding machine may be provided internally with a feed screw 33 of suitable size and pitch, and the wet material to be extruded in paste-like consistency is fed into the extrusion chamber through a suitable hopper or intake such as shown at 34. The outlet of the extruding machine may also be provided with a flexible hose 35 having at its outer end a rigid delivery nozzle 36 which the operator can move around as needed to deliver an extruded ribbon of moist raw material directly onto the surface of the molten bath in the furnace.

In accordance with my invention the raw materials, whether they be moist or dry ores, concentrates, fluxes or other material, are projected or propelled laterally into the furnace onto the surface of the molten bath of the furnace in such a manner that the material delivered will not submerge, sink or plunge into the molten bath but will be established and maintained as a floating layer having its upper surface exposed to the flame in the furnace and its under surface exposed to the stored up heat in the molten bath. This procedure makes unnecessary the pre-mixing or bedding of raw materials to be charged into the furnace since each material can be separately charged and proportioned as desired. In addition, of course, concentrates to be smelted can be delivered directly to the furnace from the filters or concentrators without intermediate treatment, and such delivery can be made by means of portable containers, conveyor belts or other suitable means. By delivering the charged materials onto the surface of the bath at a low, preferably almost horizontal angle, I have found that it is possible to charge wet raw materials into the furnace without any serious hazard of explosions.

I prefer to use a charging device which is easy for the operator to regulate and adjust, and for this purpose the slinging device illustrated in Figs. 4, 5 and 6 is particularly suitable. By swinging the machine laterally as well as up and down, the operator can deposit a fan-like thin blanket of concentrates or raw charge on the surface of the hot bath. Spreading action caused by the heat exchange and elimination of moisture and other gases cause further spreading of the blanket so that it can be readily made to cover substantially the whole area of the smelting zone of the furnace, thus presenting a maximum surface area to the flame and to the hot bath and promoting rapidity of smelting and efficient use of the furnace fuel.

The feeding method of my invention may be carried out continuously by the operator if desired, or it can be made continuous only for certain periods of time.

When the operator is about to receive molten slag from the converter department, it is a simple matter for him to prepare the bath to receive this slag so that the proper reactions take place and are controlled.

It is most desirable to reduce the higher iron oxides such as magnetite in the converter slag to ferrous oxide. The latter can then easily be combined with hot silica to produce a reverberatory furnace slag suitable for disposal. Just before the converter slag is received, the operator may spread over the bath near the converter slag launder a suitable layer of silica and reducing agent. For example in the furnace illustrated, a slinging device may be operated to deliver silica

through the charging port 26 at the end of the furnace to form a layer of silica and then to spread over this silica layer a suitable amount of sulfide concentrates, carbonaceous material or other reducing agent. Thus, when the converter slag is poured into the furnace through the launder 24 it flows out across this blanket of silicious material and reducing agent producing prompt reaction with ebullition of the bath which properly stirs and mixes the various ingredients and thus promotes the best metallurgical result at or close to the surface of the bath. Such treatment minimizes the amount of unconverted heavy oxides of iron which re-enter the matte and are re-cycled unnecessarily back to the converter department.

Also, such a treatment reduces to a minimum the amount of oxides that separate out and freeze as solid accretions on the hearth of the crucible and which eventually cut down its capacity for holding fluid matte and slag. More complete metallurgical reactions at this point in the process also reduce the amount of copper which otherwise would be retained by the slag and lost when the reverberatory furnace slag is taken to the slag dump.

The feeding method of my invention also makes possible the introduction of crushed lime rock or other fluxes and the spreading of such material over the bath at any time that such correction may be needed. In accordance with my invention, such additions can be made quickly and are almost immediately effective, whereas such corrective measures are not possible with the standard side feed furnace as heretofore operated. The feeding method of my invention further cuts down the surges which otherwise necessarily take place in the rate of liberation of sulfur. With the sulfur liberated at a more uniform rate in accordance with my feeding method, it is far easier for the operator to regulate combustion air in the furnace and thus produce more efficient use of available fuel.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. A method of feeding a reverberatory smelting furnace containing a molten bath of metalliferous materials which comprises propelling moist concentrates laterally into the furnace in the form of a compact stream unmixed with air so that said stream strikes the surface of the molten bath at a low angle to avoid plunging moist surfaces into the bath in contact with molten matte and to form and maintain a floating layer of solid material covering at least a substantial area of the molten bath.

2. A method as defined in claim 1 in which the compact stream of moist concentrates is introduced through an opening in a side wall of the furnace and the direction in which the stream is propelled into the furnace is changed from time to time to spread the concentrates around over different areas of the molten bath surface.

3. A method as defined in claim 1 in which fluxing materials are separately charged into the furnace from time to time in the same manner that the moist concentrates are charged.

4. A method as defined in claim 1 in which the raw materials charged into the furnace are propelled through a port in the furnace wall by a slinging device.

5. A method as defined in claim 1 in which the raw materials charged into the furnace are propelled through a port in the furnace wall by a pneumatic device.

6. A method as defined in claim 1 in which the moist concentrates are mixed with fluxing material before being propelled into the furnace.

7. A method of operating a copper smelting reverberatory furnace which comprises forming a molten bath of matte and slag extending substantially the full width of the furnace, establishing a layer of solid materials to be smelted floating on or near the surface and covering a substantial area of said molten bath, and maintaining said solid layer by propelling laterally into the furnace at least one ribbon-like stream of moist copper concentrates unmixed with air so that the stream strikes the surface of said molten bath or said layer at a low angle to avoid plunging moist solids below the surface of the bath and into contact with the molten matte.

8. A method as defined in claim 7 in which from time to time silica is distributed over one

area of the molten bath where converter slag is normally received, and molten converter slag is then introduced to flow over said area for reaction therewith.

5 9. A method as defined in claim 7 in which the direction in which the ribbon-like stream of concentrates is propelled into the furnace is varied from time to time to spread the concentrates over a substantial area of the molten bath.

10 CHARLES R. KUZELL.
